DOOR CLOSING DEVICE

George W. Slopa, Chicago, Ill.

Application January 8, 1945, Serial No. 571,797

10 Claims.

(Cl. 292—79)

The invention relates to improvements in door closing devices and more particularly to such a device as is particularly useful to maintain a tight seal between a refrigerator door and the door frame or jamb.

Refrigerators and other compartments requiring a tight closing of a door frequently are provided with means intended to hold the door in tight sealing engagement with the door jamb. Such known devices as are available for this purpose frequently lack efficient means to retain the door tightly closed under all conditions of use, and more particularly as when the sealing strips on the door become worn; also such known devices often become useless for the purpose intended, due to their springs becoming broken or otherwise losing their tension. It is, therefore, an object of the present invention to provide a door closing device which is effective to maintain a tight seal between a door and its jamb regardless of the condition of the sealing strips thereon, and one in which a worn out or broken spring may be easily and quickly replaced and the tension of the springs adjusted to insure proper operation of the door closer.

Another object of the invention is to provide a door closing device of the character described with novel means to facilitate adjustment of the springs therein without dismantling the device or removing it from its mounting.

Another object of the invention is to provide a door closing device of the kind having past-center springs, wherein the springs are effectively concealed within a part of the door closing device.

Another object is to provide a very durable door closing device, having few operating parts, which is easy to manufacture and assemble, positive in operation, and highly efficient.

Other and further objects of the present invention will be apparent from the following description and claims and are illustrated in the accompanying drawing which, by way of illustration, shows a preferred embodiment and the principle thereof and which is considered to be the best mode contemplated for applying that principle. Other embodiments of the invention embodying the same or equivalent principle may be used and structural changes may be made as desired by those skilled in the art without departing from the present invention and the purview of the appended claims.

In the drawing:

Fig. 1 is a front elevational view of the door closing device, showing it mounted in place.

Fig. 2 is an end elevational view of the door closing device, showing it in effective position.

Fig. 3 is a side elevational view of the device, showing the door closing element in an inoperative position.

Fig. 4 is a vertical sectional detail view taken on line 4—4 of Fig. 3.

Referring to the disclosure in the accompanying drawing, the door closing device embodying the features of the present invention is shown mounted upon the door frame or jamb 11 of a door opening and in door locking or sealing position with respect to a door 12 fitted into said door opening. The door 12 may be of any usual construction commonly incorporated in refrigerator doors and may include a sealing strip 13, arranged on its inside face 14 to have a tight sealing abutment with the face of the door jamb or frame 11 when closed. The door is provided on its free edge with a projection or bumper plate 15, which extends outwardly from the free edge of the door and includes an inclined outer face 16 which preferably merges into the plane of the outside surface of the door 12. The projection or bumper plate 15 is intended to engage the door closing device when the door is swung into either an opened or a closed position so as to actuate said device for moving it into an ineffective or an effective position.

The door closing device, generally indicated at 17, includes a mounting bracket 18, which preferably is substantially rectangular in shape and has slotted apertures 19 at each end to receive mounting screws 21 by means of which the bracket 18 is firmly secured in any required position upon the outside face of the door frame 11. The bracket 18 includes a pair of spaced apart bearing standards 22 having aligned bearing openings therein, each to receive one of a pair of trunnions 23 extending outwardly longitudinally from the end walls 24 of a rocker arm 25 which is arranged between said standards. The rocker arm 25 preferably is cast in one piece, although it will be understood as the description proceeds that it may be fabricated in any other suitable fashion, such as from sheet material or from separate parts joined together.

The rocker arm 25 is substantially hollow and it includes the side walls 24, a back wall 26, and inner and outer end walls 27 and 28 respectively. A pair of spaced parallel webs or partitions 29 are provided within the hollow rocker arm 25 and they are of such width as to extend outwardly beyond the plane of the open face of the rocker arm, as best shown in Fig. 4. The webs 29 define

a plurality of chambers 31 and 32 within the hollow cast arm and said webs further provide mounting means for a pair of rollers 33 and 34 arranged within and one at each end of the chamber 31 upon bearing pins 35.

The door closing device 17 is positioned, with respect to the projection 15 on the edge of the door 12, so that one or the other of the rollers 33 and 34 is disposed in the path of said projection when the door is being moved into opened or closed position. When the door closing device is in the ineffective position illustrated in Fig. 4, the roller 34 is so located as to be engaged by the projection 15 while the door 12 is being closed whereupon the rocker arm 25 is rotated about its pivot 23 a sufficient distance to enable the projection 15 to pass clear of the roller 34.

Means is provided within the rocker arm 25 to cause said rocker arm to be moved forcibly into the effective position best illustrated in Fig. 2 whereby the other roller 33 is brought into tight pressing engagement with the outside face of the door 12 to thereby insure a tight sealing of the door opening thereby. Such means is best illustrated in Figs. 3 and 4 and it preferably consists of a pair of tension springs 36, one mounted in each of the two chambers 32. Each of these springs is connected at one of their ends to an eyelet fitting 37 suitably mounted in the outer end wall 28 of the rocker arm and the other ends of said springs are each connected to one of a pair of threaded stems 38. The stems 38 are threadingly engaged in an internally threaded sleeve 39 carried in the bracket 18. As illustrated in detail in Fig. 4, each internally threaded sleeve 39 extends freely through the bracket 18 and is provided on its lower end with an enlarged flange 41 suitably seated in a similarly shaped recess 42 in the bottom face of said bracket. The body portion of said sleeve 39 is threaded externally and its upwardly extending free end 43 is suitably cut away to provide a hex-head which may be engaged by a wrench or other tool so as to be rotated in its mounting. Obviously, rotation of the sleeve 39 is effective to move the threaded stem 38 associated therewith upwardly or downwardly and said sleeve is locked in place by a lock nut 44 threaded thereon.

It should be observed that the connected ends of the springs 36 are in off-center relation to the trunnions 23 about which the rocker arm 25 rotates. Consequently, initial movement of the rocker arm from the ineffective position shown in Fig. 4 towards the effective position illustrated in Fig. 2, upon closing movement of the door, will carry the spring mountings past dead center with relation to the trunnions 23, whereupon the tension of the springs acts to pull the rocker arm into its lowermost or effective position, as illustrated in Fig. 2, and thus retain the door closed tightly.

When the door is moved from its closed position (Fig. 2) into an opened position, the inclined face 16 of the projection 15 engages the roller 33 to carry the rocker arm towards its ineffective position until such time as the springs 36 again move past the dead center position previously noted, whereupon said springs throw the rocker arm into its fully ineffective position as illustrated in Fig. 4.

Due to the fact that the springs 36 may lose some of their tension, because of crystallization or other causes after a prolonged period of use or because said springs may become broken and consequently require replacement, means is present in the form of the stems 38 and sleeves 39 for

adjusting the tension of the springs to thereby retain them balance and under such tension as may be required to insure effective operation of the device. Both the lock nut 44 and the hex-heads 43 on the sleeves 39 are accessible for manipulation and adjustment from the outside of the bracket 18 and consequently it is not necessary to dismantle the door closing device or to remove it from its mounting should such adjustment or replacement of a spring or springs become necessary.

Movement of the rocker arm 25 beyond a predetermined effective position, while the door is open, is prevented by providing suitable flanges 45 on each of the standards 22, as best shown in Figs. 2 and 3. These flanges are formed integral with the standards and they extend inwardly towards each other a sufficient distance to underlie the end walls 24 of the rocker arm 25.

Although a preferred embodiment of the invention has been described herein and disclosed in detail in the accompanying drawing, it should be understood that the invention is capable of embodying a variety of modifications in detail construction without departing from the spirit of the invention or the scope of the appended claims.

I claim:

1. A door closing device comprising, in combination, a bracket, a hollow rocker-arm pivoted on said bracket, said arm having a roller chamber and a spring chamber on each side of said roller chamber, rollers mounted one at each end of the roller chamber for selective engagement by a door when the latter is moved into opened and closed positions, and a spring in each spring chamber each anchored at one end to the rocker-arm and at the other end to said bracket for imparting a snap-action movement of the rocker-arm toward and from operative positions.

2. A door closing device comprising, in combination, a bracket, a hollow rocker-arm pivoted on said bracket, said arm having a roller chamber and a spring chamber on each side of said roller chamber, rollers mounted one at each end of the roller chamber for selective engagement by a door when the latter is moved into opened and closed positions, a spring in each spring chamber each anchored at one end to the rocker-arm and at the other end to said bracket for imparting a snap-action movement of the rocker-arm toward and from operative positions, and means on the bracket to adjust the force of said springs.

3. A door closing device comprising, in combination, a bracket, a hollow rocker-arm pivoted on said bracket, said arm having a roller chamber and a spring chamber on each side of said roller chamber, rollers mounted one at each end of the roller chamber for selective engagement by a door when the latter is moved into opened and closed positions, a spring in each spring chamber each anchored at one end to the rocker-arm, adjustable elements attached to the other ends of said springs, and means in said bracket engageable with said adjustable elements to adjust the force of said springs.

4. A door closing device comprising, in combination, a bracket, a hollow rocker-arm pivoted on said bracket, a pair of rollers one mounted at each end of said rocker-arm, chambers in said arm one on each side of said pair of rollers, springs one in each chamber each secured at one end to said arm and at its other end to said bracket, and means on said bracket to adjust the force of said springs.

5. A door closing device comprising, in com-

bination, a bracket, a hollow rocker-arm pivoted between its ends on said bracket, a pair of rollers one mounted at each end of said rocker-arm, chambers in said arm one on each side of said pair of rollers, springs one in each chamber each secured at one end to said arm and at its other end to said bracket, and means on said bracket to adjust the force of said springs.

6. A door closing device comprising, in combination, a bracket having spaced bearing standards, a hollow rocker-arm pivoted between said standards; a pair of spaced rollers supported on the rocker-arm in a common plane midway between the side walls of said arm, a pair of chambers in said arm one between said pair of rollers and each side wall of said arm, a spring confined within each chamber each having one end secured to the rocker-arm, and means on the bracket to which the other ends of the springs are secured adjustable to vary the force of the springs.

7. A door closing device comprising, in combination, a bracket having spaced bearing standards, a hollow rocker-arm pivoted between said standards; a pair of spaced rollers supported on the rocker-arm in a common plane midway between the side walls of said arm, a pair of chambers in said arm one between said pair of rollers and each side wall of said arm, a spring confined within each chamber each having one end secured to the rocker-arm, and its other end attached to said bracket.

8. A door closing device comprising, in combination, a bracket having spaced bearing standards, a hollow rocker-arm pivoted between said standards; a pair of spaced rollers supported on the rocker-arm in a common plane midway between the side walls of said arm, a pair of chambers in said arm one between said pair of rollers and each side wall of said arm, a spring con-

fined within each chamber each having one end secured to the rocker-arm, a pair of adjusting screws one connected to the other end of each spring, and means in said bracket engaged by said 5 adjusting screws adjustable to adjust the force of said springs.

9. A door closing device comprising, in combination, a bracket having spaced standards, a hollow rocker-arm arranged between and pivotally mounted on said standards, spaced webs in said rocker-arm, rollers arranged between and journaled in said webs one at each end of the rocker-arm, tension springs within the rocker-arm one outwardly of each web effective to impart snap-action movement to said rocker-arm, means connecting one end of each of said springs to said rocker arm, threaded stems one connected to the other end of each spring, and internally threaded sleeves in the bracket one to threadingly receive each stem, said sleeves each being rotatable to alter the position of the stems so as to adjust the force of the springs.

10. A door closing device comprising, in combination, a bracket having spaced standards, a hollow rocker-arm arranged between and pivotally mounted on said standards, spaced webs in said rocker-arm, rollers arranged between and journaled in said webs one at each end of the rocker-arm, tension springs within the rocker-arm one outwardly of each web effective to impart snap-action movement to said rocker-arm, means connecting one end of each of said springs to said rocker-arm, threaded stems one connected to the other end of each spring, internally threaded sleeves in the bracket one to threadingly receive each stem, said sleeves each being rotatable to alter the position of the stems so as to adjust the force of the springs, and means to secure said sleeves against rotation.

GEORGE W. SLOPA.
